UNITED STATES PATENT OFFICE.

WILLIAM TANKERSLEY, OF DENVER, COLORADO.

COLLAPSIBLE UMBRELLA.

1,313,966.

Specification of Letters Patent. Patented Aug. 26, 1919.

Application filed April 5, 1919. Serial No. 287,733.

To all whom it may concern:

Be it known that I, WILLIAM TANKERSLEY, a citizen of the United States, residing at Denver, in the county of Denver and State 5 of Colorado, have invented certain new and useful Improvements in Collapsible Umbrellas, of which the following is a specification, reference being had to the accompanying drawings.

10 This invention relates to an improved collapsible umbrella, and an object of the invention is to provide a device of this kind, which may be collapsed in a small compact compass, whereby the umbrella may be easily carried in a dress suit-case or the like, if 15 desired. However, it is possible to close the umbrella, and fasten the ribs together near the handle of the stick of the umbrella, so that the umbrella may be used as a walking 20 stick, if such is desired.

The invention further aims to provide a collapsible stick for the umbrella, comprising a plurality of telescopically united tubular sections, and means for holding the 25 sections in different positions, whereby the stick may be lengthened or shortened as the case may be.

A further object of the invention is the provision of means, whereby the stays and 30 the ribs of the umbrella may be collapsed, the stays having an improved means of connection with one of the sections of the stick, means being afforded for holding the section carrying the stays in different adjusted positions.

A further object of the invention is the provision of means coöoperating with the means of connection between the stays and a section of the stick, for guiding and preventing excessive twisting of the section, 40 when collapsing the stays and the ribs.

A further object of the invention is the provision of means on the stick for actuating the spring locking means between the 45 sections, so that one or more of the sections of the stick may telescopically collapse.

The invention further aims to provide means on the extremity of the handle on the stick, to engage the outer extremities of the 50 ribs, to hold the ribs closed when the stick is collapsed, and means adjacent the other end of the handle of the stick to engage the extremities of the ribs to hold the ribs closed when the stick is extended.

55 A further object of the invention is the provision of a rubber tip on the end of the

extensible stick, for protecting the end of the stick, when the umbrella is used as a walking cane.

The design of the invention as now illustrated and set forth is deemed preferable. Obviously, alterations may arise, when reducing the invention to a more practical form for commercial purposes, and the right to these alterations is claimed, provided they 65 are comprehended by what is claimed.

The invention comprises further features and combination of parts, as hereinafter set forth, shown in the drawings and 70 claimed.

In the drawings:

Figure 1 is a vertical sectional view through the umbrella showing the stick, the ribs and the stays collapsed, illustrating the 75 ribs as being held in collapsed position by the spring tension button on the extremity of the handle.

Fig. 2 is a vertical sectional view through the umbrella showing the section 3 telescopically collapsed and the ribs and stays closed, 80 the ends of the ribs being clamped by means of the sleeve 18.

Fig. 3 is a vertical sectional view through the umbrella showing it open.

Fig. 4 is a cross-sectional view on line 85 4-4 of Fig. 3.

Fig. 5 is an enlarged detail view of the ferrule 57, showing the guide rods 63.

Referring more especially to the drawings, 1 designates the stick as a whole of the 90 umbrella, and this stick comprises a plurality of telescopically united tubular sections 2, 3 and 4. For instance, a handle section, a rib supporting section, and an intermediate stay supporting section. The handle 95 section 2 telescopically fits in the handle 5, and is secured by means of a transverse pin 6. The opposite ends of the handle 5 have conventional form of ferrules 7 and 8. The handle is constructed of any suitable 100 material, preferably wood or the like and is hollow. Fitted into the end 9 of the handle is a tubular member 10, which is secured by a transverse pin 11. Fitting into the tubular member 10 is an extension 12 of a 105 button 13. The extension 12 of the button has lateral lugs 14 which play in the slot 15 of the tubular member 10. The lugs 14 are the extremities of a transverse pin, between which and the pin 11, a tensioned 110 coil spring 16 is connected, thereby urging tension on the button, to hold it in contact

with the end of the tubular member 10. This button has an annular flange 17 which flange overlies the extremities of the ribs of the umbrella, when the stick is collapsed, 5 and the ribs closed, thereby holding the ribs closed. To open the ribs, a pulling action is imparted on the button, the spring 16 being put under tension, which will release the ribs from engagement with the flange. 10 The retraction of the spring will return the button to its normal position after the ribs have been released.

A ferrule sleeve is mounted upon the section 2. This sleeve 18 has a limited sliding 15 movement between the end of the handle and a shoulder 19 on the section 2. This sleeve is also provided with an annular flange 20, which may surround the extremities of the ribs of the umbrella, when the stick is 20 extended, and the ribs closed, thereby holding the umbrella closed. The end parts 21 and 22 of the rib and stay supporting sections 4 and 3 are provided with elongated slots 23 and 24. The stay supporting and 25 handle sections are provided with transverse pins 25 and 26. These pins 25 and 26 are fixed in any suitable manner and against movement along the sections and are extended transversely through the slots 23 and 24, 30 thereby connecting the sections. However, owing to the provision of the slots, the section 4 may telescope movably in the section 3, and the section 3 be movable telescopically in the section 2, whereby the stick may be 35 collapsed or extended, as the case may be. The handle section 2 is provided with a plurality of short slots, say for instance 4 in number designated respectively 27, 28, 29 and 30. These slots are arranged in the section 40 2 so as to register with the slot 24 in the intermediate stay supporting section 3. The intermediate stay supporting section 3 carries the usual or conventional yieldable spring member 31, the lateral tongue 32 of 45 which is designed to engage in one of the slots 27 to 30 inclusive, for holding the handle section in different adjusted positions on the intermediate section. This yieldable spring member is mounted in the stay supporting section in the usual manner, for instance its lateral extremity 33 engages an opening in the wall of the section, there being a lug 34 to contact with the opposite wall of the section, thereby tensioning this 50 yieldable spring member. Mounted upon the handle section is a spring actuating sleeve 35 provided with outwardly flared projecting arms 36. These flared arms 36 constitute means to cam on the tongue 32, so 55 that the sleeve 35 may ride over the tongue and the tongue carrying end of the spring member, in order to disengage the tongue from any one of the said slots. A collar 37 is formed on the section 2 so as to limit the 60 sleeve 35 in a direction toward the handle,

in order to prevent the sleeve from being moved too close to the handle.

The intermediate stay supporting section 3 is provided with a slot 38, and the section 4 carries a yieldable spring member 39 similar in construction to the spring member 31. The tongue of the spring member 39 is designed to pass through the slot 38, whereby the section 4 may be held in adjusted positions. 75

Carried by one end of the section 3 is a collar 40, the same being secured on the section by threads 41. This collar 40 has a lateral annular flange 42, which is grooved annularly and supplied with radial slots, the 80 groove and slots being designated respectively by the characters 43 and 44. The slots are engaged by the inner ends of the stays 45, while the groove receives an annular wire 46, the wire passing through suitable apertures in the ends of the stays, thereby pivotally mounting the stays on the collar. By this construction the stays are held equally spaced. The end 47 of the section 4 has fixed thereto in any suitable manner such as indicated at 48 a rib supporting head 49. This head has an annular flange 50, which is provided with radial slots 51 and a groove 52. The groove 52 receives an annular wire 53, on which the ribs 55 are pivotally mounted. 90

The pivoted ends of the ribs 55 engage in the slots 51, thereby holding the ribs equally spaced. The collar of the head is supplied with additional slots 56, intermediate the slots 51. Loosely fitting one end of the section 3 is a ferrule 57, which is provided with extension arms 58 diametrically disposed. These arms are knurled as shown at 59, to prevent slipping of the fingers when manipulating the umbrella. The ferrule 57 is 100 provided with an annular flange 60 which is provided with radial slots 61 and a groove 62. Spaced guide rods 63 have their end portions engaging the slots 56 and 61. Obviously the wire that fastens the ribs to the 110 head, also passes through apertures of the ends of the rods which engage the slots 56, thereby holding the ribs securely connected to the head. An annular wire 64 is seated in the groove 62 and passes through apertures 115 in the opposite ends of the guide rods 63, thereby connecting the guide rods securely to the ferrule. These rods are spaced and between the rods the stays slidably engage. The outer ends of the stays are connected 120 to the ribs in the usual manner as indicated at 65. A suitable covering 66 may be supplied on the ribs, and the outer marginal portions of the same may be connected to the outer ends of the ribs as shown. The 125 tubular section 4 of the extensible stick has its end beyond the head threaded, and engaging the threaded end is a rubber tipped member 67. The opening in the covering receives the threaded end of the section 4, and 130

by means of a suitable sewing thread (not shown) the marginal portion of the covering may, in the usual manner, be whipped, so as to prevent the opening from tearing, and 5 interposed between the covering and the rubber tipped member 67 is a circular plate 68, thereby presenting a neat appearance. It is to be noted that the collar on the section 3 partly telescopes the ferrule on the section 3, 10 when the ribs of the umbrella are open.

In order to open the umbrella the button may be actuated against the action of the spring, thereby releasing the ribs. By placing the fingers of the left hand on the arms 15 of the ferrule of the section 3 and fitting the spring actuating sleeve 35 over and depressing the tongue of the spring 31 the section 3 may be moved or adjusted telescopically in the section 2, thereby extending the stick. 20 Obviously the stick may be additionally extended, if desired by again depressing the spring member 31. Then by pushing the outwardly arranged ferrule of the section 3, the stays in the ribs may be opened. It 25 is to be noted that the finger engaging pieces carried by the ferrule are disposed over the tongue of the spring member 39, so that when opening the ribs and the stays the spring member 39 may be depressed in order 30 that the section 4 may be moved telescopically in the section 3. In opening the stays and the ribs, the stays are guided, and by means of the rods excessive twisting of the umbrella with relation to the stick is 35 avoided. To close the umbrella the finger pieces of the ferrule of the section 3 may be depressed to operate the spring 39, then by moving the ferrule of the section 3 toward the handle section, and pushing the 40 section 3 in the opposite direction the stays and the ribs may be closed. When the ribs are closed, the ferrule sleeve on the section 2 may engage the extremities of the ribs. Upon examining the drawings it may 45 be obvious how the sections of the stick may be telescopically collapsed.

When the umbrella is collapsed, as shown in Fig. 1, the lateral tongue 32 of the upper spring member 31 engages in slot 29^a of the section 2 of the umbrella stick, thereby holding the stick telescopically collapsed. This tongue 32 of the upper spring member also passes through a slot 38^a of the section 3 of the umbrella stick. In Fig. 2 when the 50 section 3 is moved telescopically, so as to collapse the ribs, the lateral tongue 32 of the upper spring member also engages the slot 38^a.

The invention having been set forth, what 55 is claimed as new and useful is:

1. In a collapsible umbrella, the combination with an extensible stick comprising rib and stay supporting sections telescopically united, the stay supporting sections 60 having a slot, of a spring device carried by

the rib supporting section to engage the slot, to hold the rib supporting section extended, ribs connected to the rib supporting section, stays connected to the stay supporting section, connections between the 70 stays and the ribs, and means connecting the rib and stay supporting sections for guiding and reinforcing the stays in their spaced relations, when opening or closing the umbrella. 75

2. In a collapsible umbrella, the combination with an extensible stick comprising rib and stay supporting sections, telescopically united, ribs connected to the rib supporting section, stays connected to the ribs, 80 and in turn connected to the stay supporting section, a ferrule on the stay supporting section and through which said section movably passes, a head on the rib supporting section, and means connecting the ferrule 85 and the head for guiding the stays and reinforcing them in their spaced relations.

3. In a collapsible umbrella, the combination with an extensible stick comprising rib and stay supporting sections, telescopically united, ribs connected to the rib supporting section, stays connected to the ribs, and in turn connected to the stay supporting section, a ferrule on the stay supporting section and through which said section movably passes, a head on the rib supporting section, and means connecting the ferrule 90 and the head for guiding the stays and reinforcing them in their spaced relations, 95 means for holding the sections in extended 100 or collapsed positions and means carried by the ferrule for actuating the holding means.

4. In a collapsible umbrella, the combination with a stick comprising rib and stay supporting sections telescopically united, 105 ribs connected to the head of the supporting section, stays connected to the ribs and in turn connected to the stay supporting section, a ferrule loosely mounted upon the stay supporting section, a collar on the stay supporting section and to which the stays are connected, said collar adapted to fit into the ferrule, a head on the rib supporting section to which the ribs are connected, and spaced elongated guide rods connecting the 110 head and the ferrule, and interposed between the stays for reinforcing and guiding the stays when opening and closing the 115 umbrella.

5. In a collapsible umbrella, the combination with a stick comprising rib and stay supporting sections telescopically united, ribs connected to the head supporting section, stays connected to the ribs and in turn connected to the stay supporting section, a ferrule loosely mounted upon the stay supporting section, a collar on the stay supporting section and to which the stays are connected, said collar adapted to fit into 120 the ferrule, a head on the rib supporting 125 section, a ferrule loosely mounted upon the stay supporting section, a collar on the stay supporting section and to which the stays are connected, said collar adapted to fit into 130 the ferrule, a head on the rib supporting

- section to which the ribs are connected, and spaced elongated guide rods connecting the head and the ferrule, and interposed between the stays for reinforcing and guiding the stays when opening and closing the umbrella, means for holding the section in its adjusted positions, and means for actuating the first means.
6. In an umbrella, the combination with an extensible stick, provided with a handle, of rib and stay members on the stick for the support of the umbrella covering, a flanged button having an extension telescopically fitting the handle, spring means for the button for tensioning the same, whereby the flange of the button may surround the ends of the ribs, when closed and the stick collapses.
7. In a collapsible umbrella, the combination with a stick comprising rib and stay supporting sections telescopically united, said rib supporting section having a head, ribs pivotally connected to the head, a collar detachably fixed on one end of the stay supporting section, stays being pivotally connected to the collar and in turn pivoted to the ribs, a ferrule loosely mounted upon the stay supporting section and loosely receiving the lower portion of the collar, a plurality of guide rods arranged vertically and being spaced and connecting the head and the ferrule, said collar having guide notches intermediate where the stays are pivotally connected to the collar and receiving said spaced vertically disposed guide rods, thereby guiding the collar and its section and guiding the stays, and reinforcing them in their spaced relations.
8. In a collapsible umbrella, the combination with a stick comprising rib and stay supporting sections telescopically united, said rib supporting section having a head, ribs pivotally connected to the head, a collar detachably fixed on one end of the stay supporting section, stays being pivotally connected to the collar and in turn pivoted to the ribs, a ferrule loosely mounted upon the stay supporting section and loosely receiving the lower portion of the collar, a plurality of guide rods arranged vertically and being spaced and connecting the head and the ferrule, said collar having guide notches intermediate where the stays are pivotally connected to the collar and receiving said spaced vertically disposed guide rods, thereby guiding the collar and its section and guiding the stays, and reinforcing them in their spaced relations, means for holding the section in its adjusted positions, and means for actuating the first means.
9. In a collapsible umbrella, the combination with an extensible stick, of ribs connected to the stick, stays connected to the ribs, means on the stick to which the stays are connected, whereby the stays may be operated for collapsing the ribs, said stick having a hollow handle, a tube fixed in the hollow handle and having an end projecting beyond the handle, said projecting end having diametrically opposite slots, a flanged button having an extension fitting into the projecting end of the tube, a pin extending transversely of the extension of the button and engaging said slots, a second pin extending through the handle and through the tube, and a spring connecting the two pins to tension the button, whereby the flange of the button may overlie the ends of the ribs, when collapsed and when the stick is collapsed.
